UNITED STATES PATENT OFFICE

PAUL E. KLOPSTEG, OF EVANSTON, ILLINOIS

DESIGN FOR A GALVANOMETER OR ARTICLE OF SIMILAR NATURE

Application filed June 17, 1931. Serial No. 40,236. Term of patent 14 years.

To all whom it may concern:

Be it known that I, PAUL E. KLOPSTEG, a citizen of the United States, residing at Evanston, in the county of Cook and State of Illinois, have invented a new, original, and ornamental Design for Galvanometers, or Articles of Similar Nature, of which the following is a specification, reference being had to the accompanying drawing, forming a part thereof, wherein the galvanometer is shown in perspective.

The galvanometer comprises a base 1 to which the casing 2 is secured, and the front of the casing is closed by a glass wall 3 which exposes the galvanometer unit 4, pointer 5 and scale 6 to view.

I claim:

The ornamental design for a galvanometer or article of similar nature as shown and described.

PAUL E. KLOPSTEG.
